UNITED STATES PATENT OFFICE.

CHARLES L. LILLEBERG, OF CHICAGO, ILLINOIS, ASSIGNOR TO JOHN B. MALLERS, JR., OF CHICAGO, ILLINOIS.

CYCLOMETER.

No. 897,379

Specification of Letters Patent.

Patented Sept. 1, 1908.

Application filed February 3, 1908. Serial No. 414,111.

To all whom it may concern:

Be it known that I, CHARLES L. LILLEBERG, a citizen of the United States, and a resident of Chicago, in the county of Cook and State of Illinois, have invented certain new and useful Improvements in Cyclometers, of which the following is a clear, full, and exact description.

My invention relates to cyclometers, and 10 its object is to enable the digit wheels and gearing secured to and concentric with each, to be separated to permit of the same being reset at naught or at any number desired, and when separated held in the same relative 15 position so that when permitted to approach each other again said gear will come into perfect operative engagement, substantially as hereinafter fully described and as particularly pointed out in the claims.

20 In the drawings:—Figure 1 is a plan view of my invention. Fig. 2 is a horizontal section taken in a plane just below the upper bearings of the gearing thereof. Fig. 3 is a similar section taken on a plane just above 25 the ratchet-wheels of the stationary member. Fig. 4 is an edge view of my improved cyclometer. Figs. 5, 6 and 7 are diagrammatical views illustrating the engagement of gearing used in connection with my improvements.

Referring to the drawings A represents a rectangular or other suitably shaped supporting-plate, and B, B, the upper and lower L-shaped plates of a stationary supporting-frame, between which the revolving parts of my invention having stationary bearings are located. These L-shaped plates are, preferably, placed so that the outer edges of the longer branches of the same are parallel with 35 the longitudinal edge of the base-plate A, and these L-shaped plates are separated by columns or posts A', A' situated at the ends of the longer branch of said plates, substantially as shown. Journalized between the ends of 40 the shorter branches of the plates B, B, farthest from the longer arm thereof, is a spindle 2 whose ends are journalized in suitable bearings in said plates. Just below the upper plate a registering spur-wheel 3 is mounted 45 on this spindle the periphery described by the arms of which is sufficient to enable the objects to be counted to engage the spurs projecting beyond the end edges of said shorter branches. Next the lower plate B 50 this spindle is provided with a star-shaped wheel 4 that has equi-distant points and is

engaged by a spring-actuated arm 5 that is pivoted in any suitable manner to the base-plate A and has a head that is adapted to bear against two of the points of the star-wheel in such manner that its blunted beak enters the concavity between said points and prevents the voluntary movement thereof, substantially as shown.

Between the spur-wheel 3 and the star-wheel 4, spindle 2 is provided with a pinion 6 that engages an idle-gear 7 journalized between plates B, B, substantially as shown. Idle-gear 7 is greater in diameter than pinion 6 and engages a pinion 8 of slightly greater 70 diameter than said pinion 6 and is mounted on a spindle 9 the ends of which are journalized between plates B, B. This spindle 9 extends up through its upper bearings, and is provided with a digit-wheel 19 on its upper end, 75 the equi-distant numerals on the upper face of which near its circumferential edge, run from "0" up to "9" in numerical order. The lower end portion of spindle 9 has a ratchet wheel 10 mounted thereon that is engaged by 80 a pawl 11 and this ratchet is provided with ten teeth, and the enlarged space between these teeth is of such dimensions that the pointed beak of the pawl enters the same and prevents any independent movement of said 85 ratchet or spindle. Between the pinion 8 and the ratchet 10 a wheel 12 having but one tooth 13 is secured to spindle 9, which, once during every revolution of the spindle 9, engages suitable spaces which occur between 90 the teeth of ten equi-distant pairs of teeth in the apexes of a geneva-wheel 14. When the tooth 13 has passed out of engagement with the space in one of the apexes of the wheel 14, the circular edge of wheel 12 bears against 95 the apex in which said last mentioned space is made and the next following apex of wheel 14 and prevents the independent movement.

Wheel 14 is mounted and revolves with a spindle 15, that is journalized in the end of a 100 vibratory frame-work consisting of an upper and lower plate C, C, which are pivoted at their ends farthest from the shorter branch of the stationary supporting-frame to the base-plate, and are separated the same distance 105 apart as plates B, B, by a sleeve surrounding the pivotal bolt and by a boss 16, situated adjacent to wheel 14. The inner edge of the plates C, C, are kept bearing against the inner longitudinal edge of the longer branch of 110 plate B, B, by a spring 17 consisting of a suitable wire of steel or other material turned one

or more times around the pivotal boss 16 and having its adjacent end extend to and bear against the adjacent spacing boss of the stationary-frame, and having its longer arm extend to and bear against the boss 50, so as to keep the vibratory supporting-frame normally pressing toward and against the longer branch of the stationary-frame.

The upper end of the spindle 15 extends through its bearings and has secured thereto a "tens" digit-wheel 18. The diameter of this digit-wheel 18 is about the same as that of the digit-wheel 19 and it has on its upper circumference a series of equi-distant numerals near its circumferential edge which run from "0" to "9" in numerical order. Spindle 15 also has a wheel 20 the circumference of which is provided with one tooth similar to wheel 12, and also with a ratchet-wheel 21 that is engaged by a pawl 22, which latter is pivoted at one end to the upper plate B of the stationary frame, at a point near the entrant angle of the longer and shorter branches of the stationary-frame. The single tooth wheel 20 engages with the geneva wheel 23 mounted on a spindle 24, the ends of which are journaled in the upper and lower plates B, B, of the stationary-frame, in the same longitudinal frame as spindle 9. Mounted upon this stationary spindle 24 is a one-toothed wheel 25 and a ratchet wheel 26, and this ratchet wheel is engaged by a pawl 27 pivoted to a suitable pivot connected to the lower plate B. The one toothed wheel 25 of the spindle 24 engages with a geneva-wheel 28, journaled on a spindle 29, the ends of which latter are journaled in bearings in the upper and lower plate C of the vibratory frame. Spindle 29 is journaled in the same longitudinal plane as spindle 15, and is located at such distance therefrom as to enable it to engage with a gear on spindle 24. This spindle 29 has a ratchet wheel 30, and a single toothed wheel 31 mounted thereon and secured thereto, which latter engages a geneva-wheel 32 on spindle 34 journaled between the upper and lower plates B, B, of the stationary-frame, in the same longitudinal plane as and at the same distance from spindle 24 as spindle 24 is from spindle 9. The ratchet-wheel 30 of spindle 29 is engaged by a suitable pawl 33 that is pivoted to the upper plate B of the vibratory-frame and prevents the independent movement of the gearing on spindle 29. There is also a ratchet wheel 35 on spindle 34 that is engaged by a pawl 36, which latter is pivoted to the lower plate B of the stationary-frame, at a point intersected by a transverse plane coming midway between spindles 34 and 24.

The movable end of the vibratory frame is provided with a pin 37 projecting from its upper plate C towards its lower plate, and this pin engages the short end of a lever 38, which latter is pivoted between the shorter branches of the L-shaped plates of the sta-

tionary-frame, near the edge adjacent to the moving end of the vibratory-frame, and the longer end of this lever extends out beyond the adjacent end of the plate to provide an extension that is adapted to be readily grasped by the fingers when it is desired to move the same on its pivot, to make its shorter branch engage pin 37, and cause the vibratory-frame to move away from the longer branch of the stationary-frame, and the gearing on spindles 29 and 15 to move away from and out of engagement with the gearing and spindles 9, 24, and 34 journaled in the stationary-frame. The movement of this lever is limited by a stud projecting from a plate 39, that is secured to a bolt connecting the angle of the plates of the stationary-frame.

In operation, when the vibratory-frame is moved away from the stationary-frame the spring actuated pawls 36 and 27 (which are pivoted between the stationary plates) will be moved toward and will engage ratchet-wheels 35 and 26 by reason of the removal of the pressure of pins b, c, secured to and projecting up from the lower plate of the vibratory-frame against their shorter branches. At the same time said pawls and ratchets are engaged by each other pawls 33 and 22 engage ratchet wheels 30 and 21 by virtue of said pawls moving away from pins d, e, projecting from the upper plate of the stationary-frame. The gearing on the spindles thus being out of engagement by grasping the edges of the digit-plates between the fingers, they can be turned so as to bring any number on the digit-plate, back of the holes or openings 40 in the face-plate 41. This face-plate is flat and covers over the digit-plates of the cyclometer, and is secured in position by means of screws that are tapped into bosses 42, 42, secured to and arising from the stationary-frame in a transverse plane between the digit-plates of the same. When the vibratory frame is permitted to return toward the stationary plate, the geneva wheels thereon will be so positioned by the engagement of said pawls and ratchets, as to be immediately brought into operative engagement with the single tooth wheels, and when the gearing of the vibratory and stationary frames thus come into mesh, the pawls automatically release the ratchets engaged therewith, and the movement of the gearing would be regulated by the action of the spur-wheel as it is made to move by the engagement of the passing commodity or thing being counted.

What I claim as new is:—

1. In a cyclometer a series of suitable digit-wheels having stationary bearings, and digit-wheels alternating therewith having bearings movable simultaneously towards and from said first mentioned digit wheels, one numeral of each digit-wheel constituting

one of the numerals of the total number indicated by said cyclometer.

2. In a cyclometer a series of suitable digit-wheels, a stationary frame in which said wheels have bearings, a transversely movable frame normally pressing toward said stationary frame, and digit-wheels alternating with and normally engaging said first mentioned wheels and having bearings in 10 said movable frame.

10 3. In a cyclometer a series of suitable digit-wheels, a stationary frame in which said wheels have bearings, a movable frame pivoted at the end opposite the units digit 15 wheel in said stationary frame and normally pressing towards said stationary frame, and digit-wheels alternating with and normally engaging said first mentioned wheels and having bearings in said movable frame.

20 4. In a cyclometer a series of suitable digit-wheels, a stationary frame in which said wheels have bearings, a movable frame pivoted at one end and normally pressing towards said stationary frame, and digit-wheels 25 alternating with and normally engaging said first mentioned wheels and having bearings in said movable frame.

5. In a cyclometer a series of suitable digit-wheels having stationary bearings, 30 digit-wheels alternating therewith having bearings movable simultaneously towards and from said first mentioned digit-wheels, and means for preventing involuntary motion of said wheels when disengaged.

35 6. In a cyclometer a series of suitable digit-wheels, a stationary frame in which said wheels have bearings, a transversely movable frame normally pressing toward said stationary frame, digit-wheels alternating with and normally engaging said first 40 mentioned wheels and having bearings in said movable frame, and means for preventing involuntary motion of said wheels when said frames are separated.

45 7. In a cyclometer a series of suitable digit-wheels, a stationary frame in which said wheels have bearings, a movable frame pivoted at the end opposite the units digit wheel in said stationary frame and normally 50 pressing toward said stationary frame, digit-wheels alternating with and normally engaging said first mentioned wheels and having bearings in said movable frame, and means for preventing involuntary motion of said 55 wheels when said frames are separated.

8. In a cyclometer a series of suitable digit-wheels, a stationary frame in which said wheels have bearings, a movable frame pivoted at one end and normally pressing 60 towards said stationary frame, digit-wheels alternating with and normally engaging said first mentioned wheels and having bearings in said movable frame, and means for preventing involuntary motion of said wheels 65 when said frames are separated.

9. In a cyclometer a stationary L-shaped frame, a series of digit-wheels journaled in the longer branch of said L-shaped frame, a spring returnable vibratory frame pivoted at the end farthest from the shorter arm of said vibratory frame, a series of digit-wheels journaled in said vibratory frame and adapted to inter-communicate with the digit-wheels in the stationary frame, and means engaging the end of said vibratory frame opposite its 75 pivot for moving the same away from the longer branch of the stationary frame.

10. In a cyclometer a stationary L-shaped frame, a series of digit-wheels journaled in the longer branch of said L-shaped frame, a 80 spring returnable vibratory frame pivoted at the end farthest from the shorter arm of said vibratory frame, a series of digit-wheels journaled in said vibratory frame and adapted to inter-communicate with the digit-wheels in 85 the stationary frame, and a spring returnable lever pivoted in the shorter branch of the stationary frame and having one end adapted to engage the end of the vibratory-frame opposite its pivot to move the same 90 away from the longer branch of the stationary frame.

11. In a cyclometer a stationary L-shaped frame, a series of digit-wheels journaled in the longer branch of said L-shaped frame, a 95 spring returnable vibratory frame pivoted at the end farthest from the shorter arm of said vibratory frame, a series of digit-wheels journaled in said vibratory frame and adapted to intercommunicate with the digit-wheels in 100 the stationary frame, means engaging the end of said vibratory frame opposite its pivot for moving the same away from the longer branch of the stationary frame, and pawls for preventing the involuntary movement of said 105 digit-wheels when said vibratory frame moves away from the longer branch of the stationary-frame.

12. In a cyclometer a stationary L-shaped frame, a series of digit-wheels journaled in 110 the longer branch of said L-shaped frame, a spring returnable vibratory frame pivoted at the end farthest from the shorter arm of said vibratory frame, a series of digit-wheels journaled in said vibratory frame and adapted to 115 intercommunicate with the digit-wheels in the stationary frame, means engaging the end of said vibratory frame opposite its pivot for moving the same away from the longer branch of the stationary frame, and spring 120 actuated pawls for preventing the involuntary movement of said digit-wheels when said vibratory frame moves away from the longer branch of the stationary frame.

13. In a cyclometer a stationary L-shaped frame, a series of digit-wheels journaled in the longer branch of said L-shaped frame, a spring returnable vibratory frame pivoted at the end farthest from the shorter arm of said 125 vibratory frame, a series of digit-wheels jour- 130

- naled in said vibratory frame and adapted to intercommunicate with the digit-wheels in the stationary frame, and pawls pivoted to the stationary frame that prevent the involuntary movement of the digit-wheels journaled therein, and pawls journaled in said vibratory frame which together with said first mentioned pawls alternately operate to prevent the involuntary movement of the 10 digit-wheels journaled in the frames to which they are pivoted, when the vibratory frame moves away from the longer branch of the L-shaped frame.
14. In a cyclometer a series of suitable 15 digit wheels, a stationary frame in which said wheels have bearings, a transverse movable frame normally pressing toward said stationary frame, digit-wheels alternating with and normally engaging said first mentioned 20 wheels and having bearings in said movable frame, and pawls for preventing the involuntary movement of said digit wheels when said frames are separated.
15. In a cyclometer a series of suitable 25 digit wheels, a stationary frame in which said wheels have bearings, a movable frame pivoted at the end opposite the units digit wheel in said stationary frame and normally pressing towards said stationary frame, digit- 30 wheels alternating with and normally engaging said first mentioned wheels and having bearings in said movable frame, and pawls for preventing the involuntary movement of said digit wheels when said frames are separated.
16. In a cyclometer a series of suitable 35 digit wheels, a stationary frame in which said wheels have bearings, a movable frame pivoted at one end and normally pressing towards 40 said stationary frame, digit-wheels alternating with and normally engaging said first mentioned wheels and having bearings in said movable frame, and pawls for preventing the involuntary movement of said digit 45 wheels when said frames are separated.
17. In a cyclometer a series of suitable 50 digit-wheels, a stationary frame in which said wheels have bearings, a transversely movable frame normally pressing toward 55 said stationary frame, digit-wheels alternating with and normally engaging said first mentioned wheels and having bearings in said movable frame, pawls for preventing the involuntary movement of said digit 60 wheels when said frames are separated, and a spring actuated lever adapted to engage said vibratory frame and move the same out of engagement with said stationary frame.
18. In a cyclometer a series of suitable 65 digit wheels, a stationary frame in which said wheels have bearings, a movable frame pivoted at the end opposite the units digit wheel in said stationary frame and normally pressing towards said stationary frame, digit- 70 wheels alternating with and normally engag-
- ing said first mentioned wheels and having bearings in said movable frame, pawls for preventing the involuntary movement of said digit wheels when said frames are separated, and a spring actuated lever adapted to engage said vibratory frame and move the same out of engagement with said stationary frame.
19. In a cyclometer a series of suitable 75 digit wheels, a stationary frame in which said wheels have bearings, a movable frame pivoted at one end and normally pressing towards said stationary frame, digit-wheels alternating with and normally engaging said first mentioned wheels and having bearings 80 in said movable frame, pawls for preventing the involuntary movement of said digit-wheels when said frames are separated, and a spring actuated lever adapted to engage said vibratory frame and move the same out of engagement with said stationary frame.
20. In a cyclometer a series of suitable 85 digit wheels, a stationary frame in which the spindles of said wheels have bearings, a transversely movable frame normally pressing toward said stationary frame, digit-wheels alternating with and normally engaging said first mentioned wheels and whose spindles have bearings in said movable frame, and ratchet wheels on said spindles, and pawls engaging said ratchet wheels for preventing the involuntary movement of said wheels when said frames are separated.
21. In a cyclometer a series of suitable 90 digit wheels, a stationary frame in which the spindles of said wheels have bearings, a movable frame pivoted at the end opposite the units digit wheel in said stationary frame and normally pressing towards said stationary frame, digit-wheels alternating with and normally engaging said first mentioned wheels and whose spindles have bearings in said movable frame, ratchet wheels on said spindles, and pawls engaging said ratchet wheels for preventing the involuntary movement of 95 said wheels when said frames are separated.
22. In a cyclometer a series of suitable 100 digit-wheels, a stationary frame in which the spindles of said wheels have bearings, a movable frame pivoted at the end opposite the units digit wheel in said stationary frame and normally pressing towards said stationary frame, digit-wheels alternating with and normally engaging said first mentioned wheels and whose spindles have bearings in said movable frame, ratchet wheels on said spindles, and pawls engaging said ratchet wheels for preventing the involuntary movement of 105 said wheels when said frames are separated.
23. In a cyclometer a series of suitable 110 digit-wheels, a stationary frame in which the spindles of said wheels have bearings, a movable frame pivoted at one end, and normally pressing towards said stationary frame, digit-wheels alternating with and normally engaging said first mentioned wheels and whose spindles have bearings in said movable frame, ratchet wheels on said spindles, and pawls engaging said ratchet wheels for preventing the involuntary movement of 115 said wheels when said frames are separated.
24. In a cyclometer a series of suitable 120 digit-wheels, a stationary frame in which the spindles of said wheels have bearings, a movable frame pivoted at one end, and normally pressing towards said stationary frame, digit-wheels alternating with and normally engaging said first mentioned wheels and whose spindles have bearings in said movable frame, ratchet wheels on said spindles, and pawls engaging said ratchet wheels for preventing the involuntary movement of said wheels when said frames are separated.

In testimony whereof I have hereunto set my hand and seal this 5th day of December, 125 A. D., 1907.
